CLAIM

The ornamental design for a travel foldable potty for toddler, as shown and described.

DESCRIPTION

FIG. 1 is a front, right and top perspective view of a travel foldable potty for toddler, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is another perspective of the open state of the travel foldable potty for toddler of FIG. 1; and,

FIG. 11 is another perspective of the open state of the travel foldable potty for toddler of FIG. 1.

The broken lines depict portions of the travel foldable potty for toddler that form no part of the claimed design.

The dot-dash broken lines in FIGS. 1 and 9 depict the boundaries of the enlargements that form no part of the claimed design.

1 Claim, 11 Drawing Sheets
